US0D1112885S

(12) **United States Design Patent** (10) **Patent No.:** **US D1,112,885 S**
(45) **Date of Patent:** **** Feb. 10, 2026**

(54) **FAN LAMP**

(71) Applicant: **Zhongshan Fengmei Lighting Technology Co., Ltd.**, Zhongshan (CN)

(72) Inventors: **Zuhong Zhou**, Zhongshan (CN); **Weihai Hong**, Guangshui (CN)

(73) Assignee: **Zhongshan Fengmei Lighting Technology Co., Ltd.**, Zhongshan (CN)

(**) Term: **15 Years**

(21) Appl. No.: **29/935,984**

(22) Filed: **Apr. 4, 2024**

(51) **LOC (15) Cl.** **26-05**

(52) **U.S. Cl.**

USPC **D26/59**; D23/377

CLAIM

The ornamental design for a fan lamp, as shown and described.

DESCRIPTION

FIG. 1 is a front perspective view of a fan lamp, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the fan lamp, which form no part of the claimed design.
